DRESSMAKING TEMPLATE

Mary B. Picken, New York, N. Y.

Application March 16, 1951, Serial No. 14,519

Term of patent 7 years

(Cl. D52—1)

To all whom it may concern:

Be it known that I, Mary B. Picken, a citizen of the United States and a resident of New York city, Borough of Manhattan, in the county and State of New York, have invented a new, original, and ornamental Design for Dressmaking Template, of which the following is a specification, reference being had to the accompanying drawings, forming part thereof.

In the drawings:

Fig. 1 is a plan view of a dressmaking template embodying my new design.

Fig. 2 is a top edge view thereof.

Fig. 3 is a bottom edge view thereof.

Fig. 4 is a view of the left-hand end thereof.

Fig. 5 is a view of the right-hand end thereof.

I claim:

The ornamental design for a dressmaking template, substantially as shown.

MARY B. PICKEN.
